[57] CLAIM

The ornamental design for a cup shaped sole, as shown and described.

DESCRIPTION

FIG. 1 is a bottom plan view of a cup shaped sole showing
my new design;

FIG. 2 is a side elevational view of one side of the cup shaped sole shown in FIG. 1;

FIG. 3 is a side elevational view of the other side of the cup shaped sole shown in FIG. 1;

FIG. 4 is a front elevational view of the cup shaped sole shown in FIG. 1; and

FIG. 5 is a rear elevational view of the cup shaped sole shown in FIG. 1.

The top surface is substantially plain as shown partially in FIG. 4.

FIG. 1.

FIG. 2.

FIG. 3.

FIG. 4.

FIG. 5.
